[57] CLAIM

The ornamental design for a brassiere, as shown and described.

DESCRIPTION

FIG. 1 is a front, top and right side perspective view of a brassiere showing my new design;

FIG. 2 is a view of the outside of the brassiere in unhooked, flattened condition;

FIG. 3 is a rear, bottom and left side perspective view; and

FIG. 4 is a view of the side of the brassiere opposite that shown in FIG. 2 with the brassiere in the condition of FIG. 2.

FIG. 1

FIG. 2

FIG. 3

FIG. 4
